J. H. HILTON.
CONCRETE FORM.
APPLICATION FILED MAY 23, 1918.

1,405,212.

Patented Jan. 31, 1922.

By Hull Smith Brock & West
Attest.

UNITED STATES PATENT OFFICE.

JOHN HARRY HILTON, OF CLEVELAND, OHIO, ASSIGNOR TO THE HYDRAULIC PRESSED STEEL COMPANY, OF CLEVELAND, OHIO, A CORPORATION OF OHIO.

CONCRETE FORM.

1,405,212.

Specification of Letters Patent. Patented Jan. 31, 1922.

Application filed May 23, 1918. Serial No. 236,111.

To all whom it may concern:

Be it known that I, JOHN HARRY HILTON, a citizen of the United States, residing at Cleveland, in the county of Cuyahoga and State of Ohio, have invented a certain new and useful Improvement in Concrete Forms, of which the following is a full, clear, and exact description, reference being had to the accompanying drawings.

10 This invention relates generally to concrete forms employed in the making of cement or concrete structures, and more particularly to a form of the inverted pan type now used in the formation of ceilings and 15 roofs. In concrete forms of this general type it has been customary to provide some separate means for connecting adjacent form sections, and besides requiring separate articles of manufacture to effect this connection considerable time and labor are involved in properly placing and arranging the said connecting means and pan forms.

One object of my present invention, therefore, is to simplify and cheapen the form 20 as a whole so that great economy will be had both in manufacture and in installation for use.

The invention also has for its object to provide a concrete form capable of producing 25 a ceiling or roof of the girder, slab or dome type.

Incidentally to the above named objects, the invention involves providing a form which in itself will be capable of sustaining 35 all of the weight of the plastic mass thereby dispensing with the separate supporting and holding means heretofore employed in this type of concrete forms; and another object of the invention is to provide a concrete 40 form embodying these various characteristics which shall also be capable of expansive adjustments whereby said forms can be used for the formation of ceilings or roofs of various areas.

45 Another object of the invention is to provide a concrete form for ceilings and roofs, which, on account of its structural strength, will require a minimum amount of shoring.

With these various objects in view, the invention consists broadly in providing a concrete form of the type described with integral side supports preferably in the form of channel members, each support comprising in its make-up at least one horizontal 55 member or portion and one vertical member

or portion, said horizontal and vertical portions being united.

The invention consists also in certain novel features of construction, and the manner of combining the same, all of which will be 60 fully set forth in the detailed description and pointed out in the appended claims.

In the drawings forming a part of this specification, I have shown several embodiments of my invention and in which Fig. 1 65 is a vertical sectional view of a plurality of mold sections arranged to provide a beamed or girder ceiling; Fig. 2 is a similar view showing the mold sections arranged to provide a flat ceiling; Fig. 3 is a view 70 showing the assemblage employed for producing a crown or dome ceiling; Fig. 4 is a slightly modified construction of Fig. 1; Figs. 5 and 6 show sectional views of still further modifications; and Fig. 7 is a sectional elevation showing the manner of bridging or connecting two mold sections by means of an extension section.

In the practical embodiment of my invention I employ a sheet metal pan A of suitable thickness, said pan being made in lengths of six, eight or ten feet as desired and the width of said pan is ordinarily from twenty to twenty-four inches. This pan is given any suitable contour according to the 80 load to be carried and is used inverted as shown, a series of such pans being arranged side by side so as to provide a girder or beamed portion B of the ceiling therebetween, while the flat or slab portion C of the 85 ceiling is carried by the central portion of the pan.

Heretofore it has been customary to arrange the ends of the pans in some sort of channel support, or they have been connected by clamps or fastening means to a soffit board and these channels or supports have in turn been arranged upon stringers supported by shoring. These connecting devices, heretofore employed, are objectionable 95 owing to the multiplicity of parts which require connection either upon the upper or lower side and it is therefore with the idea of eliminating a number of these parts and providing a structure which will in itself 100 have all the strength necessary to support the forms that my present type of form has been devised and this I accomplish by providing a channel member D at each edge of the pan, each channel member having an 105 110

upright or vertical portion and upper and lower horizontal portions. In other words, the channel member stands on edge or side.

It will be noted, therefore, that the pan portion of the mold ends at the point X, and the channel member D begins at this point.

In operation, the pans with integral channel members are arranged so as to bring the upright portions of the channel members together and any suitable form of locking connection can be employed such as a slotted bolt E and key wedge F. The channel members rest upon stringers G which are arranged at suitable intervals according to the length of the pan and when the pans or mold sections are thus arranged side by side and connected together, a complete ceiling mold of the girder type is provided, and the channel members not only form a suitable means for connecting the mold sections but also provide ample supports capable of carrying the load imposed thereon.

In Fig. 7 I have shown the manner of making an extension by means of a short or intermediate pan or mold section A' which is interposed between two pans or mold sections of the adopted length. In this construction the usual stringers G rest upon a cross piece H and an intermediate stringer I is arranged centrally of the intermediate or connecting sections.

In Fig. 2 the pan or mold section A² is nearly flat and can be curved either upwardly as shown in full lines or downwardly as shown in dotted lines and as this curvature is very slight a ceiling produced upon these forms will be practically of the flat or slab formation. The channel member D is formed at each edge of the pan A² as previously described and the mold sections are united or connected together exactly the same as heretofore, the channel members also resting upon stringers and constituting the connecting support for the mold section.

In connection with the flat mold sections A², I may employ a plurality of dome or crown sections K as shown in Fig. 3, each dome or crown section K formed of sheet metal and comprising side portions K', top portion K² and foot portions K³. If desired these foot portions could be omitted. These domes or crowns K are arranged in any desired manner so far as spacing is concerned upon the flat or slab pans and then the concrete is poured as usual and the ceiling when formed will be of the dome or crown type, and it will be understood that when the flat pans are removed the domes or crowns will be removed at the same time.

In connection with the flat or slab pan sections A² provided with channel members at each edge I may also employ girder pans 85 A³ having an angle edge A⁴ at each side

thereof, the vertical end of said angle being inserted between the channel members of the slab forms, and in case flat or slab forms of channel members are not to be had, the angle members A⁴ of the pans A³ can be arranged between the vertical members of a pair of channel members D² supported upon stringers, these channel members D² being independent of the pans or forms.

In Fig. 6 I have shown the pan A³ having 75 the angle side A⁴ resting directly upon the stringers as in some instances these angle supports may be sufficient without the aid of channel members.

In each construction it will be understood 80 that slotted bolts and key wedges or other forms of locking devices are employed for locking the form sections together. After the cement or concrete has set a sufficient length of time, the locking means are moved 85 and the pans or forms taken down and this can be accomplished by removing all of the forms at once or in installments according to the nature of the work being done.

By the employment of the channel members placed together as shown, it is obvious 90 that an exceedingly strong and durable support is provided for the shaping portions of the mold, and by forming these channel members integral with the mold sections an 95 exceedingly simple and inexpensive form of mold is provided, one which can be used over and over, as the bends or angles necessary in the formation of the various channel members will provide stiff or strengthening 100 portions capable of withstanding considerable usage without indentation or other misshapement.

The concrete form constructed as herein 105 shown and described is also capable of being nested to a certain extent and the forms A³ are capable of being completely nested.

Having thus described my invention, what I claim is:—

1. The combination with a pair of forms, 110 each having depending edges, of flanged members arranged in pairs and between which the depending edges of the forms are arranged and means connecting said flanged members and depending edges.

2. The combination with a pair of forms having laterally projecting edges, said edges having depending portions, of a pair of flanged members, and means for connecting 115 said depending portions and flanged members.

3. The combination with a pair of forms having depending edges, of a second pair of forms having flanged and depending edges, a pair of flanged members, and means 120 for connecting said flanged members and the depending portions of said forms.

In testimony whereof, I hereunto affix my signature.

JOHN HARRY HILTON.
